[57] ABSTRACT

An incendiary projectile for smooth bore special purpose individual weapons comprising a flechette provided with a head consisting of a bullet jacket having a combination of incendiary mixtures therein.

**INCENDIARY PROJECTILE FOR SMOOTH BORE
SPECIAL PURPOSE INDIVIDUAL WEAPON**

The invention described herein may be manufactured, used, and licensed by or for the Government for governmental purposes without the payment to us of any royalty thereon.

Heretofore when utilization of incendiary was required artillery pieces were employed. However, due to certain inherent limitations of such pieces they had to be located remotely from the target which presented an undesirable condition in view of environmental conditions when targets such as vehicles, gasoline and ammunition dumps, and structures of wood or other flammable materials were involved. The incendiary projectile of the invention permits close-in proximity firing to the target to the exclusion of the environmental conditions and eliminates the requirement of artillery pieces which if had been used would have betrayed strategic locations.

Accordingly a principal object of the invention is a new and novel incendiary projectile for smooth bore special purpose individual weapons.

Another object of the invention is the provisions of an incendiary flechette for smooth bore special purpose individual weapons.

The novel features that are considered characteristic of the invention are set forth with particularity in the appended claims. The invention itself, however, both as to its organization and method of operation as well as additional objects and advantages thereof will be best understood from the following description when read in connection with the accompanying drawings in which:

FIG. 1 is a longitudinal cross-sectional view of a preferred embodiment of the invention; and

FIG. 2 is a transverse sectional view taken along line 2—2 of FIG. 1.

Referring to the drawings by characters of reference and more particularly to FIG. 1 wherein the incendiary flechette of the invention is generally indicated by reference numeral 10 is detailed in the following. A bullet jacket 11 fabricated from gilding metal is formed so as to have a cylindrical portion 11a adjacent its base 16 and a conically shaped nose member 12 extending forwardly of the cylindrical member. In the forward part of the interior of the nose 12 there is loaded a high sensitivity incendiary mixture 13 having a fast burning rate. Adjacent incendiary mixture 13 there is positioned a disc shaped divider 15 followed by another incendiary mixture 14 having a lower sensitivity and slower burning rate than that of incendiary mixture 13 and substantially filling that portion of the cavity of the nose member 12 between the divider 15 and cylindrical portion 11a. The divider 15 which may be of plastic or perforated metal is for the purpose of facilitating the pressing of the incendiary mixtures 13 and 14 in the nose 12 and for maintaining separation of the incendiary mixtures 13 and 14 therein. The incendiary mixtures 13 and 14 may each comprise zirconium powder in combination with a sensitizing element such as finely divided zirconium or lead styphate. The zirconium powder in mixture 14 is a coarser powder than the zirconium powder of mixture 13 whereby a slower burning rate is obtained.

The steel shaft 17 of flechette 10 is provided along the body thereof adjacent the outward end 18 with

radially spaced steel canted fins 19 for the purpose of imparting spin to the projectile during its flight. The opposite end 20 of shaft 17 is secured in the cavity of the cylindrical portion 11a of jacket 11 by means of a disc 21 affixed thereto in conjunction with a lead core 22 poured therein and filling the cavity. Thus the shaft assembly comprising shaft 17 and canted fins 19 is prevented from separating from bullet jacket 11 during the flight of flechette 10.

The complete incendiary flechette round comprises the incendiary flechette 10 which is inserted fin end into the cartridge case 23 which is provided with a propellant charge 24 completely surrounding that portion of shaft 17 assembly extending exteriorly of the bullet jacket 11. The closed end or base 25 of cartridge 23 has centrally included therein in communication with propellant 24 a primer 26 for the purpose of igniting propellant 24 which when ignited ejects flechette 10 from cartridge case 23. The cylindrical portion 11a has formed in its exterior surface adjacent base 16 a cannelure 27 into which the mouth or open end 28 of cartridge case 23 is crimped whereby the flechette 10 and cartridge case 23 are held in releasable engagement.

We claim:

1. An incendiary flechette-type projectile for use with a barreled weapon, comprising a metal-jacketed head of an exterior size approximating the interior bore 30 of the weapon barrel through which it is to be projected, the forward end of the head jacket being closed and pointed and the rearward end of the head jacket being open, an incendiary mixture disposed within the closed forward end of the metal jacket of the head, an elongated axial shaft having a radially flanged forward end projecting into the open rearward end of the head jacket and extending rearwardly of the head a distance substantially greater than the length of the head, a metallic material filling the rearward portion of the head jacket and surrounding the flanged end of the axial shaft to firmly secure the shaft in position within the head jacket, radially spaced longitudinally extending canted fins secured to the rearward portion of the axial shaft and extending from the axis of the shaft a radial distance no greater than the greatest radius of the head jacket, a cartridge case releasably attached to the jacket of the head and receiving the finned rearward portion of the elongated shaft, a propellant 50 charge carried by the cartridge case and surrounding the portion of the shaft which extends rearwardly of the head jacket, and a primer carried by the cartridge case to ignite the propellant charge and propel the head and finned shaft from the barreled weapon.

2. The projectile of claim 1 in which that portion of the incendiary mixture in the pointed forward end of the head jacket has highly sensitive and fast burning characteristics, and in which that portion of the incendiary mixture which lies between the pointed forward end of the head jacket and the metallic filling material has less sensitive and slower burning characteristics than the mixture in the pointed forward end of the jacket.

3. The projectile of claim 2 provided with a barrier means separating the two incendiary mixtures.

4. The projectile of claim 1 in which the rearward end of the head jacket is provided on its exterior sur-

face with a cannelure into which the forward end of the cartridge case is crimped to releasably attach the cartridge case to the head.
